UNITED STATES PATENT OFFICE.

ANDREW J. JOHNSON, OF CLEVELAND, OHIO, ASSIGNOR TO THE JOHNSON PERFECTION BURNER COMPANY, OF CLEVELAND, OHIO, A CORPORATION OF OHIO.

BURNER.

1,360,753.

Specification of Letters Patent. Patented Nov. 30, 1920.

Application filed November 25, 1918. Serial No. 264,039.

To all whom it may concern:

Be it known that I, ANDREW J. JOHNSON, citizen of the United States, residing at Cleveland, in the county of Cuyahoga and 5 State of Ohio, have invented certain new and useful Improvements in Burners, of which the following is a specification.

This invention relates to gas burners for use on printing presses to heat the paper for 10 the purpose of eliminating electrostatic effects and for drying the ink, thereby to do away with slip sheets and increase the speed of the press. The object of the invention is to provide an improved burner 15 of this kind which throws the heat downwardly upon the upper surface of the paper, thereby applying it, where desired, directly to the printed surface, and also enabling the burner to be used when printing on heavy 20 paper or cardboard. Another object of the invention is to provide a burner of simple compact form which can be applied to presses where the available space is limited and which is so arranged that only a portion 25 of the burner need be used when desired, say when printing narrow sheets, and which burner is inexpensive both in first cost and in gas consumption.

Further objects of the invention are in 30 part obvious and in part will appear more in detail hereinafter.

The invention comprises the burner hereinafter described and claimed.

In the drawings, which represent one suitable embodiment of the invention, Figure 35 1 is a sectional elevation on the line 1—1, Fig. 2; Fig. 2 is a sectional plan view on the line 2—2, Fig. 1; Fig. 3 is a cross section on a larger scale on the line 3—3, Fig. 1; Fig. 4 is a similar cross section on the line 40 4—4, Fig. 1, and Fig. 5 is a detail perspective view of a supporting arm.

The burner shown in the drawings comprises a main burner tube 1 of any desired 45 length according to the width of the press, and which is suitably supported and is pierced along one side to form a row or series of closely spaced small jet openings 2 in longitudinal alinement with each other. Said tube has attached thereto at intervals 50 along its upper surface a series of brackets 3, which extend horizontally outwardly from the jet side of the tube. To the under surfaces of said brackets is secured the deflecting plate 4 which may be heat insulated in any suitable manner. As shown said

plate comprises two parallel thin metal sheets 5 between which is a layer 6 of asbestos or other heat insulating material. Plate 4 fits closely at its inner edge against the 60 tube 1 and its outer portion is bent downwardly, as at 7, where the edge of one of its metal sheets is rolled around a stiff wire or reinforcing rod 8. The downwardly inclined outer tip of the plate serves as a 65 guard to confine the flame and prevent it from passing around and beyond the deflecting plate.

Just below the jet openings 2 the tube 1 carries a jet guard 9 which is shown as a 70 long narrow metal strip held by a series of clips 10 secured to the tube. This guard at its inner edge fits closely against the tube. It extends outwardly horizontally, as shown in Fig. 3, beyond the jet openings and therefore shields them from direct flow of the outer air from beneath. At the same time a very material area of the deflector plate 4 is exposed beyond the guard strip to reflect the heat downwardly upon the paper 80 passing beneath the burner.

At intervals along its length the burner may also be provided with guard fingers or paper deflectors in the form of rods 11 secured by clips 12 to the tube 1. These fingers extend outwardly below the guard strip and preferably also beyond the deflector plate 4 and at their outer ends are bent upwardly beyond the edge of said deflector plate. Fingers 11 serve to guard the paper 90 against direct contact with the flame as they guide the sheet or web beneath the burner and prevent it from entering the combustion chamber or space in front of the jet openings.

Gas may be supplied to the burner in any desired manner. The drawings show for this purpose a gas supply tube 13 communicating with a suitable regulating valve member 14, having the usual rotatably adjustable 100 needle valve spindle 15 and beyond which is the air inlet opening 16 into one side of the burner tube 1. The opposite end of said tube may be closed by a plug or otherwise with the gas supply entering only at the one end, but the drawings show said tube provided midway between its ends with a bridge wall or center plug 17 while the opposite end of said tube may be provided with a 105 regulating valve device 18 similar in all respects to the one just described. The burner tube also is provided with a series of clips 110

19 supporting a supplemental gas pipe 20
communicating by a branch 21 with the
main gas supply pipe 13, said pipe 20 de-
livering gas to the valve device 18. The
5 plug 17 stops the flow of gas beyond the
middle of the burner tube so that each half
of said tube is supplied independently of the
other half. Either half of the burner may,
therefore, be used independently of the other
10 when printing narrow sheets or cards, or
both halves may be used together if de-
sired.

The supports for the burner may be of
any suitable form and preferably comprise
15 brackets or arms connected to some part of
the burner and arranged for attachment to
the frame of the press to support the burner
in the proper position. As illustrated, one
20 end portion of the burner tube is held firmly
in a split clamp 22 on an arm comprising
two members 23, 24, one of which is slotted
longitudinally, said members being secured
25 together by the bolts 25 and the second mem-
ber 24 being provided with a suitable clamp
26 adapted to be clamped to a part of the
press frame.

The other end of the burner tube carries
a split collar 27 rigidly secured thereto by a
screw 28 and provided with a laterally pro-
30 jecting ear 27^a. This collar is adjustable cir-
cumferentially and longitudinally of the
tube to any desired position. Next to the
collar 27 is an annular collar 29 on a two
35 part arm 30 formed similarly to the arm at
the other end of the burner tube. Collar 29
is provided with two spaced lugs 31 between
which lies the ear 29. Collar 29 is a loose
40 fit on the tube. This arrangement supports
the burner on the press frame in proper posi-
tion but the burner is held rigidly at only
one end and is capable of longitudinal move-
ment at its other end. Consequently, it can
45 come and go with expansion and contraction
due to changes in temperature.

45 The burner described is very efficient.
The flames produced at the jet openings are
projected out beneath the deflector plate and
the heat therefrom is deflected downwardly
50 directly on the inked surface. The ink is
therefore, dried quickly at least to the extent
of forming a tough skin thereon. Therefore,
the use of slip sheets is unnecessary and multi-
colored printing processes or other pro-
55 cesses involving repeated printing on the
same surface may be carried out with the
several applications to the sheet while travel-
ing through a single press. Heating the
paper also eliminates static electrical effects.

What I claim is:

1. A burner for use on printing presses, 60
comprising a burner tube having a series of
jet openings along one side, a deflector mem-
ber carried by said tube above said openings
and extending horizontally outwardly there-
65 from, and a series of paper guard fingers ex-
tending outwardly from said tube below said
openings.

2. A burner for use on printing presses,
comprising a burner tube having a series of
jet openings along one side, a deflector mem-
ber carried by said tube above said openings
70 and extending horizontally outwardly there-
from, a guard plate extending outwardly
from said tube below said openings, and a
series of paper guard fingers extending out-
75 wardly from said tube below said openings.

3. A burner for use on printing presses,
comprising a burner tube having a series of
jet openings along one side, a deflector mem-
ber carried by said tube above said openings
80 and extending horizontally outwardly there-
from, a series of paper guard fingers ex-
tending outwardly from said tube below said
openings and at their outer ends bent up-
wardly beyond the edge of said deflector 85
plate.

4. A burner for use on printing presses,
comprising a burner tube having a series of
jet openings along one side, a deflector mem-
ber carried by said tube above said openings
90 and extending horizontally outwardly there-
from, a guard plate extending outwardly
from said tube below said openings, and a
series of paper guard fingers extending out-
wardly from said tube below said openings 95
and at their outer ends bent upwardly be-
yond the edge of said deflector plate.

5. A burner for use on printing presses,
comprising a burner tube having a series of
jet openings along one side, a guard plate 100
extending outwardly from said tube below
said openings, and a series of paper guard
fingers extending outwardly from said tube
below said openings.

6. A burner for use on printing presses, 105
comprising a burner tube having a series of
jet openings along one side, a guard plate
extending outwardly therefrom, a guard
plate extending outwardly from said tube
110 below said openings, and a series of paper
guard fingers extending outwardly from
said tube below said openings and at their
outer ends bent upwardly beyond the edge
of said deflector plate.

In testimony whereof I affix my signature. 115
ANDREW J. JOHNSON.
